SHOPPING CART

Michael Wahl, Searington, Long Island, N.Y., assignor to Supermarket Environments Group Incorporated, Long Island, N.Y.

Filed Mar. 21, 1973, Ser. No. 343,668

Term of patent 14 years

Int. Cl. D12—02

U.S. Cl. D12—25

FIG. 1 is a front perspective view of a shopping cart showing my new design;

FIG. 2 is a side elevational view thereof on an enlarged scale;

FIG. 3 is a front elevational view thereof on an enlarged scale;

FIG. 4 is a rear elevational view thereof on an enlarged scale; and

FIG. 5 is a top plan view thereof on an enlarged scale.

I claim:

The ornamental design for a shopping cart, substantially as shown.
